The ornamental design for a cover for a microwave container, as shown and described.

DESCRIPTION

This application is related to application Ser. No. 29/485,561, filed concurrently herewith, which is incorporated herein by reference.

FIG. 1 is a top, side and front perspective view of a cover for a microwave container showing our new design;

FIG. 2 is a bottom, side and rear perspective view thereof;

FIG. 3 is a top plan view thereof;

FIG. 4 is a bottom plan view thereof;

FIG. 5 is a front elevation view, the rear elevation being identical thereto;

FIG. 6 is a right side elevation view, the left side elevation being identical thereto;

FIG. 7 is a cross-sectional view taken along line 7-7 of FIG. 3; and,

FIG. 8 is a cross-sectional view taken along line 8-8 of FIG. 3.
